SAFETY CLAMP FOR DRILL COLLARS

Walter A. Abegg, Los Angeles, Calif., assignor, by
mesne assignments, to Abegg & Reinhold Co.,
Los Angeles, Calif., a corporation of California

Application September 15, 1947, Serial No. 774,168

8 Claims. (Cl. 24—263)

1

This invention relates to oil well equipment, and particularly pertains to a safety clamp for drill collars.

In the course of operation of drilling oil wells it is necessary at times to grip the string of pipe in a manner to support the drill string so that it may be raised or lowered incident to the drilling operations. It is desirable to provide a clamp structure which will embrace a relatively small area of the drill string to be clamped and which at the same time will make it possible for the collar to be quickly placed in position and to be quickly and easily removed therefrom. It is the principal object of the present invention, therefore, to provide a safety clamp which may be easily placed in position or removed therefrom, and which is formed of articulately connected members adapted to collectively embrace a drill collar and to positively grip and hold the same.

The present invention contemplates the provision of a safety clamp for drill collars which comprises a plurality of clamp segments articulately connected together and carrying positive pipe engaging means, the segments being provided with means whereby the composite structure may be positively set in its gripping position.

The invention is illustrated by way of example in the accompanying drawings in which:

Figure 1 is a view in plan showing the safety clamp with which the present invention is concerned.

Fig. 2 is a view in side elevation showing the clamp, the drill pipe being indicated by dotted lines.

Fig. 3 is a vertical section through one of the body segments and the contained gripping unit, taken on line 3—3 of Fig. 1.

Fig. 4 is a view of the face of an individual gripping unit, including a gripping support and carried gripping elements, taken in the direction of arrow 4 in Fig. 3.

Referring more particularly to the drawings, 10 indicates a drill string to be gripped by the clamping device, which is here generally indicated at 11. The clamping device comprises a center segment 12 and side segments 13 and 14. Viewed in plan, the center segment is arcuate in shape and is formed at its opposite ends with lugs 42. Intermediate the ends of the center segment is a boss structure 16 which normally assumes a vertical position. This boss is of a diameter greater than the width of the segment 12 and is eccentrically disposed with relation to said segment so that the upper outer edge of the boss

2

coincides substantially with the outer edge of a horizontal flange element 17 which is connected to a parallel flange element 18 by a vertical web 19 to form the body of the segment 12. By reference to Fig. 2 of the drawing it will be seen that the outer wall of the boss 16 extends downwardly and inwardly. The angle of the outer wall is here indicated as being at approximately 9½ degrees to the vertical. An eccentric bore 20 extends downwardly in the boss 16. This bore is eccentric to the upper end of the boss 16 and its center is spaced toward the inner edge of the segment 12 a shorter distance than the radius of the bore. This will cause a throat 21 to be cut through the inner face of the boss, for a purpose to be hereinafter described. In Fig. 1 of the drawing the incompletely formed portions of the outer circumference of the boss 16 and the bore 20 are indicated by dotted lines so that the relative eccentricity of these bores can be seen as well as the relationship of the circles to the inner arcuate face of the clamp segment 12. The lower end of the bore 20 is closed and is formed with a cylindrical seat 22 to receive a helical expansion spring 23. The expansion spring 23 extends upwardly and engages the eye 24 of a pin 25. The pin 25 extends upwardly through a grip support 26. The grip support 26 is substantially cylindrical and agrees in configuration with the bore 20. Thus a segment will be cut from the inner face of the cylindrical grip support agreeing in width with the opening 21 in the side of the bore 20. The springs 23 will tend to urge the grip support 26 upwardly and in view of the fact that the width of the opening 21 is less than the diameter of the bore 20 it is obvious that the grip support will be free to rotate within the bore 20 in adapting itself to the pipe to be gripped.

Formed in the flat face 27 of the grip support 40 is a series of vertically adjacent partial circular recesses 28. Extending into the grip support from the center of each recess is a reduced bore 29. As shown in Fig. 1 of the drawing, it will be seen that the ends of the bores 29 intersect the central axis of the grip support 26. Extending longitudinally of the grip support 26 and intersecting each of the bores 29 is a small bore 30 which is of a diameter to receive the pin 25. The upper end of the pin 25 has a T-shaped head 31 which engages the upper end of grip support 26 to support the pin in fixed relation to the grip support. Mounted within the circular recesses 28 and the bores 29 are gripping elements 32 with their stems 33. The stems 33 extend into the bore 29 and are formed with a central opening

34 through them which registers with the bore 30 previously described so that the pins 25 will pass through the stems 33 of the gripping elements to prevent displacement of the gripping elements and also to prevent their rotation. The faces of the gripping elements may be of any desired design to cause impingement of the face of the gripping elements with the surface of the pipe 10, thus preventing longitudinal or rotational displacement of the pipe when gripped. Formed at opposite sides of the boss 16 and extending upwardly therefrom are lugs 35 which have openings 36 through them to receive a transverse cotter pin 37 for limiting upward movement of grip support 26. The rotation of grip support 26 within its guiding bore is limited by engagement of gripping elements 32 with the body of the segment. The permitted rotative movement of grip support 26 is just sufficient to enable its lateral adjustment to fit the different sizes of pipe that may be encountered.

The side segments 13 and 14 are substantially complementary to each other. Each side segment is formed with parallel ribs 38 and 39 which at one end provide lugs 40 and 41, between which a lug 42 of the center segment 12 extends. The lug 42 is formed with a center bore 43 in register with bores 44 and 45 of the lugs 40 and 41. These registering bores receive a hinge pin 46 by which the side segments 13 and 14 are articulately connected to the center segment 12. The main body of each of the segments 13 and 14 is arcuate when considered in plan, and at a point intermediate their arcuate lengths other bosses 16 are formed which are identical in construction with the boss formed centrally of the intermediate segment 12. These bosses carry grip supports 26, each one of which provides a mounting for a plurality of gripping elements 32. Like parts of the boss and gripping structures on the side segments will be given the same numbers as the same parts on the center segment 12.

The side segment 13 is formed with an arm 57 which is forked to receive an intermediate bar 58. This bar is pivoted in position by a pivot pin 59, the axis of which is parallel to the center axis of the safety clamp. The contiguous end of the side segment 14 carries an arm, which under normal clamping conditions is substantially parallel to the arm 57 and is indicated at 60. The arm 60 at its free end is formed with a fork 61 which is at right angles to the axis of the pin 59. The outer face of the fork 61 is arcuate and concaved, as indicated at 62, and receives a washer 63, which has a complementary convex face 64 on one side and a flat face 65 on its other side. The bar 58 is formed at one free end with an eye 66. This eye 66 serves to receive the pivot pin 59 when the clamp is to be expanded for use on a larger diameter of pipe. The opposite end of the bar is formed with a threaded cylindrical portion 67 which receives a wing nut 68. The length of the threaded portion 67 is such as to insure that when the wing nut is loosened the washer 63 may swing over the pointed edges 69 of the forked portion 61 so that the arms 57 and 60 may be swung apart, and so that the safety clamp may be removed from its embracing position around the pipe 10. A pair of supporting loops 70 and 71 are secured to opposite sides of the side segments 13 and 14 of the clamp and are disposed in a substantially diametrical relation to each other at opposite sides of the normal center of the clamp.

To permit use of the clamp on pipes of widely

varying sizes, it is important that the bar or link 58 be positioned far enough radially outwardly from the pipe being gripped to prevent engagement of the bar with the pipe when the clamp is opened to a large diameter condition. For this purpose, the bar 58 is preferably so mounted that when the clamp is in its substantially smallest diameter condition of Fig. 1, that is, when the end segments 13 and 14 are in approximately their closest relation, the portion of the bar extending between the end segments is radially spaced from a line 113 extending between the centers of the gripping faces of the gripping elements carried by those end segments a distance X which is approximately as great as the distance Y from that line to the gripping face of the third and most remote gripping element.

In operation of the present invention the safety clamp is assembled as shown in the drawings. 20 When it is to be used supporting reins may be provided to engage the loops 70 and 71 and to thus carry the weight of the safety clamp as well as the weight of the string of pipe which may be supported by the clamp. The clamp is placed 25 in position by spreading the segments apart so that there will be a space between the members 57 and 60 to accommodate the pipe. When the pipe is in its proper position between the segments the portions 57 and 60 may be drawn together, after which the bar 58 carrying the screw 67 may be swung on the pivot 59 to place the threaded screw 67 between the forked arm 61. The wing nut may then be tightened, and as this takes place the gripping elements 32 will be drawn against the cylindrical face of the drill string. 30 When the arms 57 and 60 have been drawn together as tightly as possible by the wing nut 68 it will be evident that the gripping elements 32 will be forcibly held against the face of the drill pipe, and that any serrations on the faces of the gripping elements will to some extent impinge in the surface of the drill pipe. When the weight of the drill string is imposed upon the safety clamp it will be evident that sufficient engagement is present between the drill string and the gripping elements so that the gripping elements will not slip and so that the weight will tend to force the gripping elements and their 40 holders 26 downwardly in the bores 20 against the expansion of springs 23. Thus, due to the fact that the bores 20 are inclined downwardly and inwardly it will be obvious that the grip supports 26 and the gripping elements 32 will be forced downwardly and inwardly to increase their gripping action. When it is desired to remove the safety clamp the string of pipe is temporarily supported by the slips in the rotary table so that the weight will be relieved from the safety clamp. The wing nut 68 may then be loosened and 45 swung to a free position with relation to the arms of the fork 61, after which the articulate clamp structure may be unwrapped from around the drill stem.

It is obvious that the safety clamp here disclosed provides simple and effective means whereby a pipe may be positively gripped and supported, and which means is strong in construction and may be easily manipulated to place it in a gripping position or to remove it therefrom.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

1. A safety clamp for attachment to a vertically extending well pipe comprising a body including a series of pivotally connected segments adapted to extend about the pipe, means for releasably and adjustably interconnecting the end ones of said segments to fasten the body about the pipe, each of said segments containing an essentially cylindrical bore extending angularly downwardly and inwardly relative to the vertical axis of the clamp and pipe, each of said segments having an inner substantially vertical face lying in a plane spaced from the axis of the corresponding bore a distance less than the bore radius to form an opening at the inside of the segment extending along the length of the bore, a plurality of essentially cylindrical gripper mounting members guided within said angular bores respectively for both rotation and axial movement therealong, springs beneath said mounting members urging them upwardly within said bores, said mounting members having inner faces lying substantially in the planes of said inner faces of the corresponding segments in predetermined positions of the mounting members, and a plurality of gripper elements carried by said mounting members and projecting inwardly from said inner faces thereof, each of said gripper elements having an inner gripping face extending essentially axially of the clamp and at an angle to said downwardly and inwardly extending axis of the associated mounting member, said body, mounting members and gripper elements being open to extension entirely through the body of an externally straight cylindrical pipe portion engaged by said gripping faces of the gripper elements.

2. A safety clamp for attachment to a vertically extending well pipe comprising a body including a plurality of articulately connected arcuate segments adapted to extend about the pipe, means for releasably and adjustably interconnecting the end ones of said segments to fasten the body about the pipe, each of said segments containing an essentially cylindrical bore extending angularly downwardly and inwardly relative to the vertical axis of the clamp and pipe, each of said segments having an inner substantially vertical face lying in a horizontally arcuate plane spaced from the axis of the corresponding bore a distance less than the bore radius to form an opening at the inside of the segment extending along the length of the bore, a plurality of essentially cylindrical gripper mounting members guided within said angular bores respectively for both rotation and axial movement therealong, springs beneath said mounting members urging them upwardly within said bores, said mounting members having inner faces lying substantially in the planes of said inner faces of the corresponding segments in predetermined positions of the mounting members, and a plurality of gripper elements carried by said mounting members and projecting inwardly from said inner faces thereof, each of said gripper elements having an inner enlarged head portion presenting a serrated arcuate inner gripping face extending essentially axially of the clamp and at an angle to said downwardly and inwardly extending axis of the associated mounting member.

3. An adjustable device for gripping a vertically extending well pipe comprising a body including a series of pivotally interconnected seg-

ments adapted to extend about the pipe, means for releasably interconnecting end segments of said series to fasten the segments about the pipe and adjustable for fastening the segments about pipes of different diameters, a plurality of gripping units carried at the inside of said segments respectively for engaging and gripping the pipe, said gripping units having inner gripping faces essentially curved in correspondence with the outer surface of one size of pipe to be gripped, the individual gripping units being free for both swinging movement about and movement axially along circularly spaced individual axes extending angularly downwardly and inwardly relative to the vertical axis of the body and pipe, and connections individually mounting said gripping units to said body segments for said swinging and axial movements relative thereto, whereby the gripping units are free for individual lateral movement to adjust themselves to different sizes of pipe and are automatically wedged inwardly into tight engagement with the pipe upon relative downward movement thereof, said body and gripping units being open to extension entirely through the body of an externally straight cylindrical pipe portion engaged by said gripping faces of the units.

4. An adjustable device for gripping a vertically extending well pipe comprising a body including a series of pivotally interconnected segments adapted to extend about the pipe, means for releasably interconnecting end segments of said series to fasten the segments about the pipe and adjustable for fastening the segments about pipes of different diameters, said segments containing individual partial cylindrical bores extending angularly downwardly and inwardly relative to the vertical axis of the body and pipe and open along the inner sides of the segments, and a plurality of gripping units carried at the inside of said segments respectively for engaging and gripping the pipe, said units having essentially cylindrical outer portions mounted within said cylindrical bores for both limited rotation and movement axially of the bores, whereby the gripping units are free for individual lateral movement to adjust themselves to different sizes of pipe and are automatically wedged inwardly into tight engagement with the pipe upon relative downward movement thereof, said body and gripping units being open to extension entirely through the body of an externally straight cylindrical pipe portion engaged by said gripping faces of the units.

5. An adjustable device for gripping a vertically extending well pipe comprising a body including a series of pivotally interconnected segments adapted to extend about the pipe, means for releasably interconnecting end segments of said series to fasten the segments about the pipe and adjustable for fastening the segments about pipes of different diameters, said segments containing individual partial cylindrical bores extending angularly downwardly and inwardly relative to the vertical axis of the body and pipe and open along the inner sides of the segments, a plurality of gripping units carried at the inside of said segments respectively for engaging and gripping the pipe, said gripping units having inner gripping faces essentially curved in correspondence with the outer surface of one size of pipe to be gripped, said units having partial cylindrical outer portions mounted within said cylindrical bores for both limited rotation and movement axially of the bores, whereby the grip-

ping units are free for individual lateral movement to adjust themselves to different sizes of pipe and are automatically wedged inwardly into tight engagement with the pipe upon relative downward movement thereof, said body and gripping units being open to extension entirely through the body of an externally straight cylindrical pipe portion engaged by said gripping faces of the units, and a plurality of springs urging said gripping units upwardly along said axes.

6. A safety clamp for attachment to a vertically extending well pipe comprising a body including a series of only three arcuate pivotally interconnected segments adapted to extend about the pipe, means for releasably interconnecting end segments of said series to fasten the segments about the pipe and adjustable for fastening the segments about pipes of different diameters, and three gripping units carried only one at the inside of each segment for engaging and gripping the pipe, said gripping units having inner gripping faces essentially curved in correspondence with the outer surface of one size of pipe to be gripped, said segments containing individual partial cylindrical bores extending downwardly and inwardly relative to the vertical axis of the clamp and pipe and open along the inner sides of the segments, said units having partial cylindrical outer portions mounted within said cylindrical bores for both limited rotation and movement axially of the bores, whereby the gripping units are free for individual lateral movement to adjust themselves to different sizes of pipe and are automatically wedged inwardly into tight engagement with the pipe upon relative downward movement thereof, said body and gripping units being open to extension entirely through the body of an externally straight cylindrical pipe portion being engaged by said gripping faces of the units.

7. A safety clamp for attachment to a vertically extending well pipe comprising a body including a series of only three arcuate pivotally interconnected segments adapted to extend about the pipe, means for releasably interconnecting end segments of said series to fasten the segments about the pipe and adjustable for fastening the segments about pipes of different diameters, three gripping units carried only one at the inside of each segment for engaging and gripping the pipe, said gripping units having inner gripping faces essentially curved in correspondence with the outer surface of one size of pipe to be gripped, said segments containing individual partial cylindrical bores extending downwardly and inwardly relative to the vertical axis of the clamp and pipe and open along the inner sides of the segments, said bores being open at their upper ends and partially closed at their lower ends, said units having partial cylindrical outer portions mounted within said cylindrical bores for both limited rotation and movement axially of the bores, whereby the gripping units are free for individual lateral movement to adjust themselves to different sizes of pipe and are automatically wedged inwardly into tight engagement with the pipe upon relative downward movement thereof, said

body and gripping units being open to extension entirely through the body of an externally straight cylindrical pipe portion being engaged by said gripping faces of the units, three springs contained within the lower ends of said bores and acting to urge said gripping units upwardly and outwardly, and means limiting upward movement of said units within the bores.

8. An adjustable safety clamp for gripping a vertically extending well pipe comprising a body including a series of only three pivotally interconnected segments adapted to extend about the pipe and containing individual essentially cylindrical bores extending angularly downwardly and inwardly relative to the vertical axis of the body and pipe, a link pivotally carried by one of the end segments of said series and adapted to releasably interconnect the two end segments in any of a plurality of adjusted conditions to clamp the body about any of different sizes of pipe, and only three substantially evenly circularly spaced gripping units mounted at the inside of said segments and having essentially cylindrical outer portions mounted within said bores for both limited rotation and movement axially of the bores, whereby each of said units is free for both bodily lateral movement relative to the associated segment for adjustment to different sizes of pipe and bodily movement angularly downwardly and inwardly relative to the axis of the clamp and pipe, the portion of said link extending between said end segments when retained in their closest relation being radially spaced from a line joining the centers of the gripping faces of the gripping units carried by said end segments a distance about as great as the distance between said line and the face of the most distant gripping unit therefrom.
